UNITED STATES PATENT OFFICE.

COURTLAND J. CRAWLEY, OF CHICAGO, ILLINOIS, ASSIGNOR OF ONE-HALF TO WALDO N. FERREIRA, OF CHICAGO, ILLINOIS.

CASTER.

1,404,743.

Specification of Letters Patent. Patented Jan. 31, 1922.

Application filed February 23, 1921. Serial No. 447,343.

To all whom it may concern:

Be it known that I, COURTLAND J. CRAWLEY, a citizen of the United States, residing at Chicago, in the county of Cook and State 5 of Illinois, have invented certain new and useful Improvements in Casters, of which the following is a description.

My invention belongs to that general class of devices known as casters which are generally used for supporting articles of furniture 10 or the like.

My invention has among its objects the production of a device of the kind described which is simple, convenient, compact, durable, reliable, efficient, and satisfactory for 15 use wherever found applicable.

The invention has particularly for an object the production of a device of the kind described which may be adjusted to vary the 20 height of the article supported, above the floor, and is especially useful when applied to legs of tables or other articles of furniture. When a plurality of casters are applied to such an article of furniture, each 25 of my improved casters may be individually adjusted so that each caster has an equal bearing upon the floor.

Many other objects of the construction herein shown and described will be obvious 30 to those skilled in the art to which this invention belongs from the disclosure herein given.

To this end my invention consists in the novel construction, arrangement and combination of parts herein shown and described 35 and more particularly pointed out in the claims.

In the drawings, wherein like reference characters indicate like or corresponding 40 parts;

Figure 1 is a vertical elevation of my improved caster as applied to an article to be supported;

Figure 2 is a vertical section of the same 45 with parts in elevation;

Figure 3 is a horizontal section on the line 3—3 of Figure 2;

Figure 4 is a horizontal section on the line 4—4 of Figure 2;

50 Figure 5 is a vertical section illustrating a modified form of adjusting means;

Figure 6 is a horizontal section taken on line 6—6 of Figure 5; and

Figure 7 is a horizontal section taken on 55 line 7—7 of Figure 5.

In the embodiment of my invention, as illustrated in the drawings, 1 indicates a roller-caster adapted to be inserted in any suitable article of furniture 2, or other suitable body to be supported, said caster comprising a roller 3 freely mounted so as to be revoluble on an axle 4, said axle being supported between the downturned parallel lugs or ears 5 struck up on a bracket plate 6, the manner of constructing and assembling said 60 roller, axle and bracket support being well known in the art.

Pivotedly secured to the plate 6, centrally thereof, as by upsetting the end or by threading and applying a nut thereto, or in any 70 other suitable and equivalent manner, is a shank 7, said shank portion having secured thereto, at its base, above the plate 6, a flanged cup or raceway 8 which is adapted to cooperate with the plate 6 so as to permit anti-friction ball-bearings 9 or the like to be inserted therebetween and transmit the load with a minimum of friction from the shank to the bracket plate. The shank portion 7, is threaded exteriorly at 10, and has a longitudinal peripheral slot or groove 11 therein for a purpose to be hereinafter described. 75

A hollow sleeve, socket shell or casing 12 is adapted to surround the shank 10 and to be inserted within a bore 12' provided in 85 the article to be supported, said sleeve being preferably slightly larger than the bore and split at one end, as at 13, so that it may be reduced in diameter at said end and driven into the bore and frictionally held therein. 90 In order to more securely hold the sleeve in place, there is provided a flanged disk 14 at the base of said sleeve and having a series of circumferential apertures or the like 17 therein, said flanged disk having peripheral 95 teeth 15 adapted to be driven into the material of the article being supported. A threaded plug 16 is preferably secured to the base of the sleeve substantially concentric within the disk 14, said plug forming a 100 web across the bottom of said shell or sleeve and being adapted to be threadedly movable on the shank 7 and thus provide longitudinal adjustment between the shank and sleeve parts.

A washer 18, preferably dished as shown, and of any suitable size and shape, is bored centrally thereof, and there is formed a lug 19 projecting into said bore, said lug being of a size and shape so as to enter the slot 11 110

in the shank when it is positioned thereon, so that the washer 18 may be slid longitudinally of the shank but will prevent any relative rotational movement therebetween. 5 An upstanding lug or projection 20 is provided on the upper surface of the washer, said projection being positioned at such a radial distance from the bore of said washer that it is adapted to enter any of the circumferentially spaced recesses 17 in the disk 14, and when the lug 20 is engaged within any of the recesses 17 and will lock and prevent rotational movement of the sleeve 12 upon the shank 7. The washer 18 is prevented 10 from rotational movement on the shank 7 by the tongue and slot arrangement, and as it is locked to the sleeve 12 by the projection and recess it will necessarily prevent the sleeve from rotation, unless the pin 20 is 15 released from the recess 17.

A spring or other resilient means 21 is preferably positioned between the cup 8 and the washer 18 so as to yieldably hold the washer against the disk 14, and when 25 it is desired to adjust the article being supported by the caster, the washer 18 is moved downwardly against the spring pressure so that the lug 20 is disengaged from the recesses 17 and the shank 7 may then be 30 turned to lengthen or shorten the overall length from the floor to the top of the sleeve. When the desired adjustment has been obtained the washer 18 is released, and as the spring constantly bears against 35 it a partial turn will enable the lug 20 to spring into place in its cooperating recess 17, thus securely locking the parts against accidental disengagement.

In the modification shown in Figures 5 40 to 7 inclusive, the construction is similar, except that another means is used to prevent relative rotation between the washer 18 and the shank 7. In this modification the shank is flattened as at 22, or may be 45 otherwise made suitably non-circular and the washer is also correspondingly bored non-circular, as shown, having a flattened side 23 which is adapted to be slidably mounted on the shank 7, but having no rotational movement thereon.

From the above description it will be seen that I provide a caster which is adjustable longitudinally of its shank and one wherein said adjustment may be easily and 55 quickly performed, and locked in its adjusted position.

Having thus described my invention it is obvious that various immaterial modifi-

cations may be made in the same without departing from the spirit of my invention; 60 hence I do not wish to be understood as limiting myself to the exact form, arrangement, construction and combination of parts herein shown and described, or uses mentioned. 65

What I claim as new and desire to secure by Letters Patent is:

1. In a device of the kind described and in combination, a caster comprising a roller, a spindle rotatably secured thereto, a socket shell surrounding said spindle and adapted to be fixedly secured to a body to be supported, a web member arranged transversely of said shell at one end thereof, said spindle being out of contact with said shell and 70 engageable with said web member so that the spindle may be adjusted axially of said shell, and means for yieldably locking said parts in their adjusted positions. 75

2. In a device of the kind described and in combination, a caster comprising a roller, an axle therefor, a bracket supporting said axle, an externally threaded spindle pivotally connected to said bracket at one end, a socket shell surrounding said spindle and 80 adapted to be fixedly secured to a body to be supported, a web arranged transversely of said shell at one end thereof, said web having a threaded aperture centrally therethrough engageable by the 85 threaded spindle whereby said spindle may be adjustable axially of said shell, said spindle being out of engagement with the peripheral wall of said shell throughout its length, and means for detachably and 90 yieldably locking said spindle to said fixed shell. 95

3. In a device of the kind described and in combination, a caster comprising a roller, an axle therefor, a bracket supporting said axle, an externally threaded spindle pivotally connected to said bracket at one end, a socket shell having a transverse web at 100 one end engageable with said threaded spindle, a washer non-rotatable on said 105 spindle but longitudinally slidably thereon, and means for yieldably locking said washer to said shell to maintain the spindle in its adjusted position.

In testimony whereof, I have hereunto signed my name in the presence of two 110 subscribing witnesses.

COURTLAND J. CRAWLEY.
